UNITED STATES PATENT OFFICE.

DANIEL C. STAUFFER, OF CANTON, OHIO.

CONSTRUCTION OF BUILDINGS.

No. 830,747.

Specification of Letters Patent.

Patented Sept. 11, 1906.

Application filed August 10, 1905. Serial No. 273,588.

To all whom it may concern:

Be it known that I, DANIEL C. STAUFFER, a citizen of the United States, residing at Canton, in the county of Stark and State of Ohio, have invented a new and useful Construction of Buildings, of which the following is a specification.

This invention relates to the construction of buildings, and more particularly to a novel form of mold for constructing the walls, partitions, and other portions of the building from cement, concrete, or similar plaster material.

The object of the invention is to provide a comparatively simple, inexpensive, and durable device of this character, in which the several parts may be quickly and conveniently assembled and firmly maintained in position during the molding operation, and one which will permit the continuous operation of the mold during the formation of the wall.

A further object of the invention is to provide a flexible connection between the several mold-sections designed to be embedded in the concrete or cement and adapted to be cut or severed when the cement sets to thereby permit the removal of the mold-sections, said flexible connection being left embedded in the wall so as to strengthen and reinforce the latter.

With these and other objects in view the invention consists in the construction and novel combination and arrangement of parts hereinafter fully described, illustrated in the accompanying drawings, and pointed out in the claims hereto appended, it being understood that various changes in form, proportions, and minor details of construction may be resorted to without departing from the principle or sacrificing any of the advantages of the invention.

In the accompanying drawings, forming a part of this specification, Figure 1 is a side elevation, partly in section, of a portion of a wall constructed with my improved mold. Fig. 2 is a top plan view of the same. Fig. 3 is an enlarged vertical sectional view. Fig. 4 is a transverse sectional view showing a portion of the mold used for constructing window-sills and that portion of the wall adjacent the windows.

Similar numerals of reference indicate corresponding parts in all the figures of the drawings.

55 In constructing the cement or concrete

wall I employ one or more mold-sections, each comprising an inner wall 5 and an outer wall 6, said walls being reinforced and strengthened at their top and bottom edges by longitudinally-disposed L-shaped angle-irons 7, to which said walls are riveted or otherwise rigidly secured and which also serve to support the several mold-sections in vertical alinement during the formation of the wall.

The outer walls 6 of the mold-sections are preferably oblong in shape and stamped, pressed, or otherwise roughened, so as to give the exposed surface of the wall the appearance of cut or chipped rock, the longitudinal edges of the walls 5 and 6 being bent or curved inwardly, as indicated at 8, to produce inwardly-extending flanges which form depressions in the wall and serve to define the several blocks comprising the latter. If desired, however, some of the plates comprising the outer wall 6 may be smooth or unobstructed, as indicated at 9, whereby certain of the blocks in the wall will present a smooth-dressed surface, thereby adding to the ornamental appearance of said wall.

8. The angle bars or irons 7 are provided with a plurality of spaced openings 10, adapted to register with each other when the mold-sections are disposed in superposed relation, as shown in Fig. 3, said openings being designed to receive coupling pins or members 11, which also serve as a means for fastening the ends of the transverse connecting-wires or tie-rods 12.

The wires or tie-rods 12 temporarily retain the lower ends of the walls 5 and 6 in engagement with the adjacent faces of the molded wall 13 during the formation of the latter and until the cement, concrete, or other material sets or hardens, when the wires are cut or severed close to the wall to permit the removal of the mold-sections, and said wires left embedded in the cement so as to reinforce and strengthen the wall.

100 The side walls of the several mold-sections are secured in spaced relation to each other by means of a transverse channel-bar 14, having a series of spaced openings 15 formed in one end thereof and provided at its opposite end with a depending pivoted clamping member 16. The free end of the clamping member 16 is designed to bear against the angle-bars 7 of the mold-sections, while its opposite end is provided with a laterally-projecting head 17, which extends a short dis-

- tance above the bar 14 to permit the insertion of a locking wedge or key 18. Slidably mounted between the depending flanges 19 of the bar 14 is a movable clamping member 20, adapted to engage the angle-bars on the inner walls of the mold-sections, said clamping member being adjustable longitudinally of the bar 14 to permit the formation of walls of different thicknesses and securely locked 10 in adjusted position by a bolt or similar fastening device 21, passing through one of the openings in the bar 14 and engaging a corresponding opening 22 in the angular extension 23 of said clamping member, as shown.
- 15 In practice the lower mold-section is first placed in position, with the pivoted ends of the sliding clamping members engaging the angle-irons 7, after which the wires 12 are stretched across the top of the mold and the 20 ends thereof coiled or otherwise fastened to the pins 11, the cement, concrete, or other plaster material being subsequently shoveled or otherwise introduced between the walls of the mold and thoroughly tamped.
- 25 The upper mold-section is then placed upon the lower section and the ends of the connecting-wires fastened to the heads of the pins, as best shown in Fig. 3 of the drawings. After the cement in the lower mold-section has set 30 or hardened the flexible wires connecting the lower ends of the side walls are cut or severed close to the surface of the cement, which permits the ready detachment of said lower section, the wires being left embedded in the 35 wall, thereby reinforcing and strengthening the latter and permitting the continuous operation of the mold during the formation of said wall.
- In some cases the walls may be formed 40 with vertical flues or air-chambers 24 by positioning suitable core members 25 between the side walls of the mold-sections and elevating or drawing said cores upwardly as the height of the wall increases.
- 45 In Fig. 4 of the drawings there is illustrated a section of a mold for constructing that portion of the wall adjacent to the windows of the building, the outer wall 6' of the mold being formed with an auxiliary mold-section 27 for forming the window-sill. In this case a wooden nailing-block 28 is inserted between the side wall of the mold, to which may be secured the window-casing 29, there being also a pair of core members 30, 50 carried by a metal plate 31, positioned between said side walls, for forming suitable openings for the reception of the sash-weights of the window.
- From the foregoing description it will be 60 seen that there is provided an extremely simple and inexpensive device admirably adapted for the attainment of the ends in view.

Having thus described the invention, what is claimed is—

1. A mold for concrete constructions comprising a plurality of mold-sections each consisting of spaced plates having their opposite longitudinal edges bent inwardly and provided with longitudinally-disposed reinforcing bars, pins detachably secured to the bars and tie-rods connecting said sections and having their opposite ends secured to the pins, said rods being adapted to be severed and left embedded in the concrete when the mold-sections are removed. 75

2. A mold comprising a plurality of mold-sections, a bar extending transversely across the top of said sections, a depending clamping member slidably mounted on the bar at one end thereof, a clamping member pivoted to the opposite end of the bar and provided with a laterally-extending head, and a locking-key adapted to engage said head and bar, respectively, for forcing the clamping members into engagement with the adjacent 85 mold-sections.

3. A mold consisting of a plurality of superposed mold-sections each comprising an outer and an inner wall provided with longitudinal reinforcing bars adapted to engage the reinforcing-bars of adjacent sections, a perforated bar extending transversely across the upper mold-sections, a depending clamping member slidably mounted on the bar at one end thereof and adapted to engage the reinforcing-bar on one of the walls of the adjacent mold-sections, a clamping member pivoted to the opposite end of the bar for engagement with the reinforcing-bar on the other wall of said mold-section, and a fastening means passing through the perforations in the transverse bar and engaging the slidably-clamping member for locking the latter in adjusted position. 100

4. A mold for concrete constructions comprising a plurality of superposed mold-sections each provided with perforated, longitudinally-disposed angle-irons adapted to engage the angle-irons of adjacent mold-sections, removable pins seated in said perforations and serving to align adjacent mold-sections, and flexible tie-rods connecting the mold-sections and having their opposite ends fastened to said pins, said rods being adapted to be severed and left embedded in the concrete when the mold-sections are detached. 110

In testimony that I claim the foregoing as my own I have hereto affixed my signature in the presence of two witnesses.

DANIEL C. STAUFFER.
